UNITED STATES PATENT OFFICE.

NINON LANGTON, OF CLARE, LOUISIANA.

DIAPEL-CLEANER.

1,093,939.

Specification of Letters Patent. Patented Apr. 21, 1914.

Application filed May 26, 1913. Serial No. 769,956.

To all whom it may concern:

Be it known that I, NINON LANGTON, a citizen of the United States, residing at Clare, in the parish of Sabine and State of Louisiana, have invented certain new and useful Improvements in Diaper-Cleaners, of which the following is a specification, reference being had to the accompanying drawings.

10 This invention relates to diaper cleaners, and an object thereof is the provision of a device of this character comprising a handle having a scraping blade secured thereto.

Another object of this invention is the 15 provision of a cleaner comprising a handle having a scraping blade secured thereto, the blade being curved to prevent the matter which is scraped upon the blade from being deposited upon the handle.

20 Still another object of this invention is the provision of a cleaner, the blade of which is curved on one edge to form a tube whereby the blade may be secured to a handle, the body portion of the blade being curved longitudinally and transversely so that the 25 deposits scraped upon the plate will be prevented from passing over the edges thereof.

With these and other objects in view, my invention consists in certain novel constructions, combinations and arrangements of parts to be hereinafter more fully described, claimed and illustrated in the accompanying drawings, in which—

Figure 1 is a perspective view of my invention; Fig. 2 is a sectional view on the line 2—2 of Fig. 1; Fig. 3 is a side elevation of the device; and Fig. 4 is an end view thereof.

Referring more particularly to the drawings, the numeral 1 designates the handle of my device and 2 the substantially rectangular scraping blade. One edge of the blade is curled to form a tube 3, in which one end of the handle is secured by screws or other 40 suitable fastening devices 4. The body portion of the plate is curved upwardly adjacent the tube 3 to form a rib 5, the rib being

inclined rearwardly to prevent any deposit upon the plate from passing over the rib on to the handle or tube. The body portion of 50 the plate is also curved transversely and longitudinally to dispose the edges thereof above the central portion, to form a central seat or depression in which the deposits scraped from the diaper are adapted to rest. 55

In the practical use of my device, the handle is grasped and the plate moved over the surface of the diaper with the edge of the plate opposite the rib 5 in engagement with the cloth so that the deposit is scraped 60 upon the upper face of the plate.

A cleaner of this character constructed in accordance with my device comprises only two main parts, whereby it may be cheaply manufactured and it will be seen that should 65 the plate become broken or otherwise unfit for use, it may be readily detached from the handle by removing the screws 4 so that a new plate may be attached.

Having thus fully described my invention, what I desire to claim and secure by Letters Patent is:—

1. A device of the character described comprising a substantially rectangular plate curled at one edge to form a tube, said plate 75 being curved adjacent said tube to form a longitudinally extending upstanding rib, and a handle mounted in one end of said tube, as and for the purpose described.

2. A device of the character described 80 comprising a substantially rectangular plate curled at one edge to form a tube, a handle mounted at one end in said tube, said plate being curved adjacent said tube to form a longitudinally extending upstanding rib, 85 said plate being also curved longitudinally and transversely, as and for the purpose described.

In testimony whereof I hereunto affix my signature in the presence of two witnesses. 90

NINON LANGTON.
